UNITED STATES PATENT OFFICE

157,806

ADJUSTABLE SWIVEL MOUNTING FOR A NOZZLE

Doyle C. Warren, Monrovia, Calif., assignor to
Chiksan Company, Brea, Calif., a corporation
of California

Application May 11, 1948, Serial No. 146,279

Term of patent 14 years

(Cl. D91—1)

To all whom it may concern:

Be it known that I, Doyle C. Warren, a citizen of the United States, residing in the city of Monrovia, county of Los Angeles, and State of California, have invented a new, original, and ornamental Design for an Adjustable Swivel Mounting for a Nozzle, of which the following is a specification, reference being had to the accompanying drawing, forming a part thereof.

Fig. 1 is a perspective view of an adjustable swivel mounting for a nozzle, showing my new design, as viewed from the top and one side, and Fig. 2 is a perspective view of the adjustable swivel mounting for a nozzle viewed from the bottom and the opposite side thereof.

I claim:

The ornamental design for an adjustable swivel mounting for a nozzle, as shown.

DOYLE C. WARREN.
